PROTECTIVE DEVICE FOR TUBE
ENVELOPES

Norman B. Krim, Newton Highlands, Mass., assignor, by meane assignments, to Raytheon Manufacturing Company, Newton, Mass., a corporation of Delaware

Application December 9, 1943, Serial No. 513,576

10 Claims. (Cl. 250—27.5)

1 This invention relates to electron discharge tubes, and more particularly to smaller types of said tubes.

One of the objects of the present invention is to provide a tube with a protective reinforcing member adapted compressively to embrace and thus strengthen the entire tube, or a part thereof provided with said reinforcing member.

Another object of the present invention is to make said protective reinforcing member of plastic, preferably polystyrene.

These and such other aims and objects of the invention as may hereinafter appear will be readily understood from the following description, taken in connection with the accompanying drawing of embodiments of the invention herein given for illustrative purposes.

In the drawing:

Fig. 1 is a vertical cross-section of a tube embodying one illustrative form of the present invention;

Fig. 2 is a vertical section on line 2—2 of Fig. 1;

Fig. 3 is a fragmentary section taken along line 3—3 of Fig. 4 illustrating the application of the invention to a tube having relatively rigid conductors bent to increase the spacing of their external contact prongs;

Fig. 4 is a bottom plan view of Fig. 3;

Fig. 5 is a fragmentary section illustrating the application of the invention to a tube having a special arrangement of the sealing and lead-in wires for the same purpose as in Fig. 3; and

Figs. 6, 7 and 8 are vertical cross-sections of additional embodiments of the invention as applied to the "acorn" type of tube.

Referring to Figs. 1 and 2, the illustrative embodiment of the invention therein shown comprises an envelope 2 of glass or other suitable material within which is suitably supported the usual electrode assembly 4. A plurality of relatively stiff conductors 6, sealed through an external press 8, formed by softening the glass at that point and compressing it around said conductors 6, project from the under surface of said press 8, their free ends serving as external contact prongs.

In accordance with the present invention protective means is provided adapted to protect and reinforce said press 8, said means herein comprising a reinforcing member 10 of moldable material preferably a plastic, attached to said press, in any suitable manner, as by being molded thereon, or being placed thereon and heated to the proper elevated temperature, so that upon cooling said member will be found to be welded to the surface of said press 8. The plastic known as

2 polystyrene is eminently suited for this purpose as it is by nature quite resilient and resistant to shocks.

One of the features of the invention consists in the fact that said reinforcing member 10 surrounds or embraces and tends to compress said press. As the coefficient of expansion of the reinforcing material, polystyrene, for example, is considerably greater than that of glass, said reinforcing member, when cooled, will contract considerably more than will the glass and will thus exert a strong compressive force upon said press 8 at all points of its perimeter, whereby said press will be greatly strengthened, it being well known that when glass is placed under high compression its strength to withstand shock is greatly increased.

In order to be efficient, the plastic member 10 should be relatively thick, but the diameter of said reinforcing member should preferably not exceed that of the tube.

Where relatively stiff conductors project from the wall of a tube, for example from the press 8 in Figs. 1 and 2, and are used as contact prongs 6 which are plugged directly into a suitable socket, experience has demonstrated that the glass through which the conductors extend has a tendency to chip or break, if the contact prongs are subjected to any substantial transverse thrust. Such a thrust may occur on insertion of the prongs in their socket, if they do not correctly and readily fit into the holes in the socket. Great accuracy has therefore been required in the manufacture of the tube and of the socket. Experience has also shown that a considerable number of these tubes are rendered undesirable after manufacture and in use because of such fracture or breakage. The present invention overcomes the difficulties above set forth, as any thrust on the external prongs will be taken up by the reinforcing member and cannot reach the glass press.

Figs. 3 and 4 illustrate the application of the present invention to tubes in which the entire lead-in wire and contact prong are formed of a single relatively stiff wire, the wire being either pre-bent or post-bent to increase the spacing of the prongs.

Here also the pre-bent or post-bent conductors 6 are firmly welded in the reinforcing member and any shock or thrust to which the prongs 6 or said member may be subjected will be absorbed by said reinforcing member. It has been demonstrated that the prongs 6 may be bent practically at will without injury to the press 8. The thrust

on said prongs is absorbed by said reinforcing member and does not extend to said press.

Fig. 5 illustrates the present invention as it can be applied to a tube in which the relatively flexible sealing wires 11 (which may be of the type known as Dumet) are bent to enable the contact prongs 15 of relatively stiff wire to which they are joined, to be more widely spaced.

In this case the relatively stiff conductors serving as external contact prongs 15 do not extend through the press, but terminate in said reinforcing member. Nevertheless these contact prongs 15 are so firmly welded and held in said reinforcing member that they function efficiently as external contact prongs, and any shock or thrust to which they may be subjected will not be communicated through them to the press, but will be absorbed by the reinforcing member in which they are anchored and which is by nature quite resilient and resistant to shocks. This makes it possible to use said relatively stiff conductors as external contact prongs, for which relatively flexible wire is less suited, and on the other hand to use the relatively flexible wire, Dumet type, for example, for sealing through the press.

In Fig. 6 the invention is shown in its application to tubes of the type known as acorn tubes. These tubes are provided with a plurality of external lateral contact prongs, only two of which are shown in the drawing. In this illustrative embodiment of the invention the tube comprises an envelope of glass or other suitable material made in two parts 12 and 13 fused together and containing the usual electrode assembly 14 and provided with the usual exhaust tip 16. Relatively flexible sealing wires 18 are sealed through the lateral wall of said envelope, for example, between the flanges 17 of said two parts 12 and 13, the free ends of said sealing wires 18 being joined to the inner ends of relatively stiff conductors 22 forming external contact prongs. Said sealing wires 18 may and preferably will be of the type known as Dumet.

In accordance with the present invention a plastic reinforcing member 24, preferably of polystyrene, encircles said envelope and completely covers said flanges 17 of said two parts 12 and 13, the joined ends of said sealing wires 18 and of the conductors 22 being enclosed within said reinforcing member 24.

Said reinforcing member 24 may be applied in the same manner as that above described for applying the reinforcing member 16 of Figs. 1 and 2 and with the same remarkably advantageous results, and will not only reinforce and protect the points where said sealing wires 18 are sealed through the wall of envelope 12, namely the flanges 17, but by its compressive action upon the wall of the tube, will also reinforce and greatly strengthen the whole tube structure.

In the illustrative embodiment of the invention shown in Fig. 7, the tube comprises an envelope 25 of glass or other suitable material, containing the usual electrode assembly 26. It is provided with the usual exhaust tip 28. Relatively flexible sealing wires 32 have their free ends joined to the inner ends of relatively stiff conductors 34 forming external contact prongs. Said sealing wires 32 may and preferably will be of the type known as Dumet. The plastic reinforcing member 36, of polystyrene for example, encircles the envelope 25, and the joined ends of said sealing wires 32 and conductors 34 are enclosed within said reinforcing member 36. If desired said exhaust tip 28 may be provided with a plastic rein-

forcing member 40 in accordance with the present invention. The reinforcing members 36 and 40 may be applied in the same manner as described in case of reinforcing member 16 of Figs. 1 and 2, and will effectively protect and reinforce the parts they cover and add to the general strength of the entire structure.

The addition of the reinforcing member to the tube of Fig. 7 does not increase the standard dimensions of an acorn type tube. This is a distinct advantage as the tube with the reinforcing member will still be interchangeable with previous acorn type tubes.

The illustrative embodiment of the invention shown in Fig. 8 comprises an envelope 28 of glass or other suitable material which contains the usual electrode assembly 30 and is provided with a ground-off exhaust tip 42.

Said tube is made in two parts 32 and 38 joined together by outwardly projecting flanges 37 and 39.

Lateral conductors 41 are sealed in the wall of said envelope, said conductors being herein sealed between said flanges 37 and 39 encircling said envelope 28. Another conductor 44 is sealed through the top wall of said envelope and a further conductor 45 is sealed through the exhaust tip 42.

In this illustrative form of the invention the protective, reinforcing member 42 of plastic, preferably polystyrene, in accordance with the present invention, completely encloses said envelope 28, said ground-off exhaust tip 42 and said flanges 37 and 39 out to their edges. Said reinforcing member 42 may be applied in the same manner as set forth above in the description of the embodiment shown in Figs. 1 and 2 with the result that said reinforcing member 42 will not only protect and reinforce said flanges 37 and 39, and particularly those points through which said conductors 41, 44 and 45 issue, but by its compressive action from all sides will greatly add to the strength of the whole structure. In this case, as in the case of the tube of Fig. 7, addition of the plastic reinforcing member to the tube does not increase the standard dimensions of an acorn tube.

It will be apparent that the plastic reinforcing member could envelope and enclose the outer edges of said flanges 37 and 39, and that such a variation would clearly fall within the scope of the present invention.

Wherever the word "plurality" occurs in the specification and claims, said word is to be understood as meaning "two or more."

I am aware that the present invention can be embodied in other specific forms without departing from the spirit or essential attributes thereof, and I therefore desire the present description to be considered in all respects as illustrative and not restrictive, reference being had to the appended claims rather than to the foregoing description to indicate the scope of the invention.

What is claimed is:

1. In an electron discharge tube the combination of an hermetically sealed glass envelope, a reinforcing member of polystyrene attached directly to the outer surface of said envelope, relatively stiff conductors sealed through the part of said envelope to which said reinforcing member is attached and through said reinforcing member, said reinforcing member compressively embracing the part of said envelope to which it is attached, and said conductors being securely anchored in said reinforcing member and projecting therefrom as external contact prongs.

2. In an electron discharge tube the combination of an hermetically sealed glass envelope provided with an external press, a reinforcing member of polystyrene plastic attached directly to the outer surface of said press, relatively stiff conductors sealed through said press and through said reinforcing member, said reinforcing member compressively embracing said press, and said conductors being securely anchored in said reinforcing member and projecting therefrom as external contact prongs.

3. In an electron discharge tube, the combination of an hermetically sealed glass envelope; a plurality of conductors sealed through different parts of the wall of said envelope; and a reinforcing member attached directly to the outer surface of said envelope and compressively embracing the parts of said envelope through which said conductors are sealed, said conductors being securely anchored in said reinforcing member and projecting therefrom as external contact prongs.

4. In an electron discharge tube, the combination of an hermetically sealed glass envelope; a plurality of lead-in conductors spaced from one another around said envelope and sealed through the wall of said envelope in a transverse plane of the latter; and a reinforcing member encircling said envelope and compressively embracing said envelope and those parts thereof through which said conductors are sealed, said conductors being securely anchored in said reinforcing member and projecting therefrom as external contact prongs.

5. In an electron discharge tube, the combination of an hermetically sealed glass envelope; a plurality of conductors spaced from one another around said envelope and sealed through the lateral wall of said envelope in a transverse plane of the latter; and a reinforcing member attached directly to the outer surface of said envelope and compressively embracing said envelope and the parts thereof through which said conductors are sealed, said conductors being securely anchored in said reinforcing member and projecting therefrom as external contact prongs.

6. In an electron discharge tube the combination of an hermetically sealed glass envelope, a conductor sealed through the top wall of said envelope, a conductor sealed through the bottom wall of said envelope, a plurality of conductors sealed through the lateral wall of said envelope in spaced relation around the latter in a transverse plane of said envelope, and a reinforcing member directly attached to and compressively embracing said envelope including the parts thereof through which said conductors are sealed, said conductors being securely anchored in said reinforcing member and projecting therefrom as external contact prongs.

7. In an electron discharge tube, the combination of an hermetically sealed glass envelope; a plurality of relatively flexible sealing wires sealed through the wall of said envelope in spaced relation around the latter in a transverse plane thereof, a reinforcing member attached directly to the outer surface of said envelope and encircling and compressively embracing said envelope and the parts thereof through which said sealing wires are sealed; and a relatively stiff conductor joined to each of said sealing wires within said reinforcing member, said conductors being securely anchored in said reinforcing mem-

ber and projecting therefrom as external contact prongs.

8. In an electron discharge tube the combination of an hermetically sealed glass envelope, a reinforcing member of moldable material attached directly to the outer surface of said envelope, relatively stiff conductors sealed through the part of said envelope to which said reinforcing member is attached and through said reinforcing member, said reinforcing member compressively embracing the part of said envelope to which it is attached and said conductors being securely anchored in said reinforcing member and projecting therefrom as external contact prongs.

9. In an electron discharge tube the combination of an hermetically sealed glass envelope provided with an external press, a reinforcing member attached directly to the outer surface of said press and compressively embracing the same, and aligned relatively stiff conductors sealed through said press and through said reinforcing member, alternate conductors being bent laterally out of alignment in one direction and intervening conductors being bent out of alignment in the opposite direction, the free ends of said conductors being then bent back into parallelism with their original alignment, said conductors being securely anchored in said reinforcing member and their free ends projecting from said reinforcing member as external contact prongs in staggered relation in at least two parallel planes.

10. In an electron discharge tube the combination of an hermetically sealed glass envelope provided with an external press, a reinforcing member attached directly to the outer surface of said press and compressively embracing the same, and aligned relatively flexible sealing wires sealed through said press, alternate sealing wires being bent laterally out of alignment in one direction and intervening sealing wires being bent laterally out of alignment in the opposite direction, within said reinforcing member, the free ends of said wires being joined to relatively stiff lead-in conductors securely anchored in said reinforcing member and projecting therefrom in staggered relation in at least two parallel planes as external contact prongs.
